CARRIER FOR TUMBLERS

Nicholas P. Angelakos, Brooklyn, N.Y., assignor to Lancaster Colony Corporation, Columbus, Ohio, a corporation of Delaware

Filed Sept. 19, 1962, Ser. No. 71,775

Term of patent 14 years

(Cl. D58—26)

FIG. 1

FIG. 2

FIG. 4

FIG. 3

FIG. 5

FIG. 1 is a perspective view of a carrier for tumblers, showing my new design;

FIG. 2 is a top plan view thereof;

FIG. 3 is a bottom plan view thereof;

FIG. 4 is a side elevational view thereof; and

FIG. 5 is an end elevational view thereof.

I claim:

The ornamental design for a carrier for tumblers, substantially as shown.
